CLOSED CIRCUIT TELEVISION CAMERA EXTERIOR HOUSING

Raymond V. Pagano, Doraville, Ga., assignor to
L.N.P. & Associates

Filed Apr. 12, 1974, Ser. No. 460,431

Term of patent 14 years

Int. Cl. D16—01

U.S. Cl. D61—1 Q

FIG 1

FIG 4

FIG 2

FIG 5

FIG 3

FIG 6

FIG. 1 is a perspective view of a closed circuit television camera exterior housing showing my new design;

FIG. 2 is a side elevational view thereof, the side opposite being a mirror image;

FIG. 3 is a top plan view thereof;

FIG. 4 is a rear elevational view thereof;

FIG. 5 is a front elevational view thereof; and

FIG. 6 is a bottom plan view thereof.

I claim:

The ornamental design for a closed circuit television camera exterior housing, as shown and described.
